LOOSE-LEAF BINDER

Phillip Witz, Denison, Tex.

Application May 16, 1952, Serial No. 288,149

1 Claim. (Cl. 129—25)

1

This invention relates to loose leaf binders and more particularly to a binder or cover for retaining paper sheets having printed or other matter thereon and constituting forms, tables, charts or other compilations of information, in close association with each other and with the binder and for protecting such sheets against damage.

It is among the objects of the invention to provide an improved loose leaf binder or cover which will engage sheets of sheet material, such as paper, along one edge of each sheet and secure a plurality of sheets firmly in the binder; which is entirely free of all metal parts on its external surface; which, when closed, completely covers the sheets or leaves therein and is secured to the leaves in a manner to preclude loosening of the leaves in the binder and damage to the leaves; which is flexible in character and of light weight; and which is simple and durable in construction, economical to manufacture, and neat and attractive in appearance.

Other objects and advantages will become apparent from a consideration of the following description and the appended claim in conjunction with the accompanying drawing, wherein:

Figure 1 is a perspective view of a loose leaf binder illustrative of the invention;

Figure 2 is a fragmentary cross sectional view on the line 2—2 of Figure 1;

Figure 3 is a fragmentary perspective view of the binder with the parts thereof in partly assembled condition to illustrate the relationship of the several parts to each other;

Figure 4 is a fragmentary cross sectional view on the line 4—4 of Figure 1; and

Figure 5 is a fragmentary cross sectional view on the line 5—5 of Figure 2.

With continued reference to the drawing, the binder has a two part back the two parts of which are generally indicated at 10 and 11 respectively and are secured together by a hinge strip 12.

The back part 10 includes a back board 13 of rectangular shape and formed of a stiff sheet material, such as heavy paper or compressed fibre, resiliently resistant to bending and the part 11 includes a back board 14 similar to the board 13. The two back boards 13 and 14 are disposed in side by side and coterminous relationship with their adjacent edges in spaced apart and substantially parallel relationship and binding strips 15 and 16 extend respectively along the mutually adjacent edges of the boards 13 and 14.

The binding strip 15 has a longitudinally extending portion 17 overlapping and secured to

2

the board 13 along the edge of the latter adjacent the board 14 and has a doubled, longitudinally extending portion 18 extending angularly from the board 13 along the edge of the latter adjacent the board 14.

The binding strip 16 has a longitudinally extending portion 19 overlapping the board 14 along the edge of the latter adjacent the board 13 and a doubled, longitudinally extending portion 20 projecting angularly from the board 14 along the edge of the latter adjacent the board 13. The binding strip portions 17 and 19 are disposed at corresponding sides of the boards 13 and 14 and the binding strip portions 18 and 20 project from the same sides of the back boards and inwardly of the completed folder.

A stiffening bar 21 of elongated, rectangular shape extends through the doubled portion 18 of the binding strip 15 and this bar and the portion of the binding strip in which it is received are provided with spaced apart apertures 22 of elongated, rectangular shape. A stiffening bar 23, similar to the bar 22, extends through the doubled portion of the binding strip 20 and the bar 23 and the bar-receiving portion of the binding strip 20 are provided with spaced apart apertures of elongated, rectangular shape, as illustrated in Figure 3, the apertures in the bar 23 and strip 20 being in alignment transversely of the two binding strips with corresponding apertures in the bar 22 and strip 18.

The binding strips 15 and 16 are provided along their adjacent longitudinal side edges with flanges 17 and 19 respectively which are secured to the back boards 13 and 14 by wire staples 24, as illustrated in Figure 4, which extend through the back boards and binding strips at spaced apart locations along the binding strips and the binding strips may also be cemented to the back boards, if desired.

The hinge strip 12 is a strip of flexible sheet material of elongated, rectangular shape and extends across the space between the adjacent edges of the back boards 13 and 14 and marginally overlaps and is secured to the flanges 17 and 19 of the binding strips 15 and 16 secured to the back boards at the sides of the binding strip portions remote from the corresponding back boards. An outer cover 25 extends over and is secured to the surface of the back strip 12 remote from the back boards 13 and 14 and the adjacent surfaces of the back boards, this cover being preferably cemented to the back boards and the hinge strip. The back strip 12 covers all of the staples 24 connecting the bind-

ing strips to the back boards so that no part of these metal staples is exposed at the outer side of the binder and all of the other metal parts of the binder are disposed within the binder.

Protecting strips 26 and 27 extend along the mutually adjacent edges of the back boards 13 and 14 respectively in overlapping relationship to the corresponding marginal portions of the back boards at the sides of the latter remote from the outer cover 25 and lining sheets 28 and 29, of sheet material of rectangular shape, cover and are secured to the surfaces of the backing boards 13 and 14 remote from the outer cover 25 and the surfaces of the protecting strips 26 and 27 remote from the corresponding back boards.

The lining sheets are preferably firmly cemented to the back boards and protecting strips, and the outer cover is likewise cemented to the back boards and to the hinge strips to completely cover and conceal the back boards.

Rivets 30 of well known construction, each including a pair of juxtaposed flat legs joined together at one end of the rivet and a head secured on the rivet at the end thereof at which the legs are joined together, extend through the aligned apertures in the binding strips 15 and 16 and are removable from the binding strips in order to remove sheets from or place sheets between the binding strips.

The sheets, as indicated at 31 in Figure 2, have apertures punched therein in spaced apart locations along the one longitudinal edge of each sheet and the sheets are placed in the binder with the edges thereof adjacent the apertures therein disposed between the portions 18 and 20 of the binding strips 15 and 16, with corresponding apertures in the several sheets in registry with each other and in alignment with the corresponding apertures in the binding strips and the stiffening bars 21 and 23. The rivets or staples 30 are then inserted through the registering apertures in the binding strips and the sheets and the ends of the legs of the rivets remote from the heads thereof are bent over, as shown in Figure 4, to firmly secure the sheets in the binder. The rectangular shape of the apertures in the binding strips and reinforcing bars hold the rivets in a predetermined position relative to the binding strips and against any freedom of rotational movement so that the sheets are firmly held and cannot become loose in the

binder and the apertures in the sheets will not be enlarged by the rivets.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claim are, therefore, intended to be embraced therein.

What is claimed is:

15 An extensible loose leaf binder comprising a pair of resilient coextensive stiffening bars having registering longitudinally spaced shank receiving openings extending therethrough, a binding strip of flexible material enclosing each 20 stiffening bar, a flange carried by and extending outwardly from one longitudinal side edge of each binding strip, a back board adhesively and mechanically fastened to each flange and projecting outwardly from the longitudinal side edge 25 thereof remote from its respective stiffening bar, said back boards being coextensive and adapted to cover leaves supported between the stiffening bars, a flexible protecting strip adhesively secured to each back board adjacent 30 the edge thereof adjacent its respective binding strip and on the side of said back board remote from its respective flange for covering the mechanical fastening means, a lining sheet coextensive with and adhesively secured to each back board in covering relation to the protecting strip, a flexible hinge strip adhesively secured adjacent its longitudinal side edges to the flanges in covering relation to the mechanical fasteners, and a flexible cover adhesively secured 35 to the back boards and to the hinge strip, and said cover having panels which are coextensive with the back boards.

PHILLIP WITZ.
